UNITED STATES PATENT OFFICE.

WILLIAM J. MCGRATH, OF CLEVELAND, OHIO.

OFFICE FURNITURE.

SPECIFICATION forming part of Letters Patent No. 517,122, dated March 27, 1894.

Application filed July 11, 1892. Serial No. 439,722. (No model.)

To all whom it may concern:

Be it known that I, WILLIAM J. MCGRATH, a citizen of the United States, residing at Cleveland, in the county of Cuyahoga and State of Ohio, have invented certain new and useful Improvements in Office Furniture; and I do hereby declare that the following is a full, clear, and exact description of the invention, which will enable others skilled in the art to which it appertains to make and use the same.

My invention relates to office furniture, and the invention consists in an article of furniture constructed and combined substantially as shown and described and particularly pointed out in the claim.

In the accompanying drawings Figure 1 is a side elevation of my new and improved article of furniture, and Fig. 2 is a transverse section thereof on line x, x , Fig. 1. Fig. 3 is a detail of the locking mechanism for the revolving case, and Fig. 4 an enlarged cross section showing the groove for the sliding flexible cover or curtain that comes down to cover the case. Fig. 5 is a perspective view of the cabinet with everything omitted from its top, and Fig. 6 is a cross section horizontally on a line corresponding to y, y , Fig. 5.

In this article of furniture, which is designed more especially for railway offices, although it may be used in other offices as well, I have kept in view the needs of an office of this kind and have combined what I consider all the essential elements thereof, which comprise storing room for letter and other books, blanks of different kinds, a wringer and place for keeping the cloths for taking letter-press copies, a stand for the letter press, and table or shelf room to lay papers, the whole being compassed in a single article of manufacture and occupying the least amount of space practicable in an article which possesses all these advantages and uses. To the end that such an article may be constructed, I employ a suitable frame, which consists essentially of the sides A, the top or cover, B, and the bottom, C. The frame thus constructed is rectangular in shape, and in this instance the sides and bottom are made plain and as wide as the structure requires, and the top or cover B overlaps all around, and has a lateral extension, b, at one side upon which I place the wringer, D.

It is customary in railroad offices to use cloths for taking letter-press copies, and these are usually kept in a tank or vessel containing water, in which the cloths are kept wet and ready to be wrung out by means of the wringer D. I therefore secure a tank or receptacle E to and beneath the extension b of the top and cover, and this tank in turn is provided with its own separate cover e at one or both sides of the wringer D, as may be preferred, so that the said cover e can be raised and the cloths taken out and wrung and the water will drop back into said tank, when the cover is restored. Said tank is provided with suitable valved outlets e' in its bottom.

Upon the opposite end or side of the cover from the wringer is placed the letter-press F, and there is room between the said letter-press and the wringer D on top of the cover B to place papers, books, and the like, to be used as an ordinary table would be. Beneath the said cover B there is a sliding board or shelf G, which is adapted to be drawn out upon either side of the cabinet as may be desired, and which affords additional shelf room when one is engaged in taking letter-press copies or the like, if such additional room be needed. This shelf is here shown as provided with parallel grooves, g, on its bottom, and pins or projections g' in the board beneath engage in said grooves and limit the movement of the shelf from side to side, one pin serving as the limit when it moves in one direction, and the other as a limit in the opposite direction. Any other sufficient means for stopping the shelf in either direction may be adopted. Beneath the said shelf and between the sides A of the frame, is a cross board H, and the said shelf rests upon this cross board and slides between it and the top of the table or cover B.

K is a revolving case which has spindles, k, provided with bearings in the bottom C and the cross board H, respectively. This case is square, and hence is made sufficiently smaller than the inside space of the cabinet to allow the case to revolve on its pivots and not touch at its corners. This revolving case is designed to provide room for letter and other books at one side, and to this end I provide the case with suitable files or compart-

ments k' , as seen in elevation in Fig. 1, and upon the opposite side of the said case are a number of drawers, k^2 , as seen in Fig. 2, in which anything may be kept that is adapted 5 to be placed therein, such as letter files, blank forms, and the like.

At the rear, and between the files or compartments k' and the drawers k^2 there is an open space or well subdivided by a partition 10 wall k^3 , extended across the case and leaving a free space between said division wall and the rear of said files and drawers. Along the front of the sides of the said case, upon the inside thereof, are vertical grooves, m , and 15 above the said files and said drawers, and between said parts and the cross board H , there is likewise a space in which the flexible sliding curtains M , N , are adapted to travel. These curtains ride over suitable sheaves, m' , 20 so as to be easily moved, and their edges are confined in the grooves or channels m . When the said flexible curtains are moved up and back they drop into the well at the rear, as shown, for example, in Fig. 2, and when they 25 are drawn forward the limit of their movement is in the grooves m to the bottom of the case. Both curtains stay where they are put by their own gravity.

At one side of the frame A is a pivoted 30 latch a , extending through the side of the frame and engaging a catch k^4 on the case K . When the latch is lifted the case is free to be revolved, and when down it holds the case against revolving.

35 It will be noticed that upon opposite sides of the cabinet or frame are vertical panels S ,

which extend inward so as to slightly overlap the respective edges of the fronts of the case when it is at rest. The cabinet or frame is made just large enough to allow the case to 40 revolve therein, and is closed at its ends A and the panels S , at the corners partly close the open sides as shown, and the case is contained and revolved wholly within this cabinet. The frame itself is in a sense complete 45 without the top B , especially so far as the rotation of the case is concerned, and this case is provided with flexible covers on opposite sides adapted each to drop into the well or space in the center of the case provided for 50 this purpose.

Having thus described my invention, what I claim as new, and desire to secure by Letters Patent, is—

The new article of furniture herein de- 55 scribed, consisting of the substantially rectangular frame constructed with closed ends and partly closed sides and flat top and bottom, the revolving case pivoted centrally in the top and bottom of said frame and having 60 compartments on opposite sides, and an open space between said compartments extending the full depth of the case, and flexible covers over the front of said compartments adapted to slide into said open space, substantially as 65 described.

Witness my hand to the foregoing specification this 28th day of June, 1892.

WILLIAM J. MCGRATH.
